TOY EXTENSION LADDER ASSEMBLY

Aubrey Robert Mills, London, England

Application October 1, 1948, Serial No. 52,291
In Great Britain June 18, 1948

11 Claims. (Cl. 46—132)

1

This invention relates to an improved extension ladder and operating arrangement therefor.

The invention arrangement is particularly adaptable to an extension ladder for a toy or model fire truck, and when used as such, gives a simulation of a fireman climbing an aerial ladder as the latter is raised, and descending the ladder as the latter is lowered.

Preferably, the extension or aerial ladder of the invention includes a first or inner section pivoted to a ladder platform for swinging between a stored and a raised position. A second or outer section is telescopically related with the inner section for extension and retraction relative thereto. To simulate a climbing or descending fireman, a slide is telescopically related with the outer section and carries the figure of a fireman in climbing position.

In a preferred arrangement, the aerial ladder is spring biased to a raised position and cranked to a stored position, with means being provided to lock the crank to hold the ladder stored. A cable is secured between the crank and the inner end of the slide, and a second cable is secured to the outer end of the slide, passes around a pulley on the outer end of the outer ladder section, and is secured to a fixed point at the inner end of the inner ladder section. A third cable extends from a fixed point on the truck around a pulley on the outer end of the inner ladder section and is secured to the outer ladder section adjacent the inner end thereof.

As the spring raises the ladder, the third cable draws out the outer ladder section. This, in turn, draws out the slide, making the figure appear to climb the ladder. When the crank is wound to lower the ladder, the first cable pulls the slide inwardly. This causes the second cable to retract the outer ladder section, drawing in the third cable. The length of the third cable between the ladder and the truck thus is shortened, swinging the ladder to the stored position.

It is accordingly an object of the invention to provide a novel extension ladder arrangement.

Another object is to provide a novel operating mechanism for aerial or extension ladders.

A further object is to provide a life-like simulation of a fireman ascending and descending an aerial ladder as the latter is raised and lowered.

These, and other objects, advantages and novel features of the invention, will be apparent from the following description and the accompanying drawings.

2

In the drawings:

Fig. 1 is a side elevation view of a model fire truck embodying the invention.

Fig. 2 is a horizontal sectional view on the line 5 2—2 of Fig. 1.

Fig. 3 is an end elevational view on the line 3—3 of Fig. 1.

Fig. 4 is a partial elevation view of the side of the truck opposite that shown in Fig. 1, illustrating a latching arrangement.

Fig. 5 is a schematic sectional view illustrating the ladder operating mechanism.

Fig. 6 is a bottom plan view of the extension ladder.

Fig. 7 is a sectional view of the ladder on the line 7—7 of Fig. 6.

Fig. 8 is a side elevation view of the movable section of the ladder.

Figs. 9 and 10 are transverse sectional views of the ladder on the lines 9—9 and 10—10 of Fig. 6, respectively.

Referring to Fig. 1, the invention is shown as embodied in a model fire truck 15 having a body 16 and wheels 17 which may be driven by a suitable motor, if desired. Body 16 has a seat 18 on which a model fireman 19 may be placed, and rearwardly of seat 18 is an extension ladder platform 21 carrying the extension ladder 20 comprising a lower section 30 and an upper section 40.

Platform 21 has a pair of spaced, vertical brackets 22 between which extends a horizontal pivot shaft 23. A coil spring 24 embraces shaft 23 and has one end 26 anchored in platform 21. The other end 27 of spring 24 bears against a flat portion 28 of the lower section 30 of ladder assembly 20. Section 30 has a pair of downwardly extending flanges 31 fitting between brackets 22 and pivoted on shaft 23. Spring 24 is arranged to bias ladder assembly 20 to swing clockwise, or upwardly about shaft 23.

Ladder section 30 is preferably an integral or one-piece member having inwardly facing channel rails 32 for the portion of its length above flanges 31. Simulated guard rails are formed by flanges 33 extending outwardly just beyond flanges 31. The flat portion 28 and rungs 34 interconnect the lower flanges of the channel rails 32 and, for a purpose made clear herein-after, portion 28 and rungs 34 have central, upwardly opening depressions 36. At its upper end, section 30 has a pair of downturned ears 37 rotatably supporting a roller 38 having a central groove 39.

55 Outer ladder section 40 has channel rails 41.

slidably fitting in rails 32 and having their lower flanges integral with spaced rungs 42. At its outer end, section 40 has a pair of downturned ears 43 rotatably supporting a grooved roller 44.

As may be best seen in Figs. 1 and 7, a model fireman 45 is mounted in climbing position on ladder 20. For this purpose, the figure 45 is mounted on a slide 50 having reduced lateral extensions 51 slidably engaged in the channelled rails 41 of ladder section 40, as may be best seen in Fig. 9. Slide 50 has a hook 52 at its outer end and an eye 53 at its inner end.

A crank 60 is used to retract the ladder 20 against the bias of spring 24. Crank 60 is rotatably mounted between side walls 14, 14 of truck 15, and includes a crank handle 61 at one end and a radial arm 62 at the other end. Intermediate walls 14, crank 60 carries a stop 63. The crank 60 may slide axially between walls 14 to allow arm 62 to be engaged and disengaged relative to a pair of spaced ribs 64, 64 on one wall 14.

Crank 60 has secured to it one end of a cable 65 which lies in rung depressions 36 and is secured at its outer end to the eye 53 of slide 50. A second cable 70 is secured at one end to hook 52 of slide 50 and the other end of cable 70 is secured to an inner fixed portion of ladder 20, for example, to the end of spring 24. Cable 70 extends over roller 44 on the outer end of section 40. A third cable 75 is secured at one end to one of the innermost rungs 42 of section 40 and extends over the roller 38 on the outer end of section 30. The other end of cable 75 is secured to a suitable point on the front end of truck 15. For example, it may be laid in a notch 11 of bumper 12 and tied beneath the bumper.

The described arrangement operates in the following manner. Upon unlatching of crank 60, spring 24, which is under tension, biases ladder assembly 20 upwardly. As assembly 20 is swung upwardly, cable 75 is pulled over roller 38. This slides section 40 outwardly relative to section 30. The upward movement of section 40 causes cable 70 to be drawn over pulley 44, drawing slide 50 and figure 45 outwardly along section 40. Meanwhile, crank 60 having been unlatched from locking ribs 64, cable 65 unwinds as slide 50 draws the same outwardly along depressions 36.

When crank 60 is turned to wind in cable 65, slide 50 is pulled inwardly, drawing cable 70 over pulley 44 and consequently sliding section 40 back along section 30. As section 40 moves inwardly, it pulls cable 75 over roller or pulley 38, shortening the cable length between this pulley and bumper 12. This swings section 30 and thereby the entire assembly 20 downwardly to the lowered position shown in dotted outline in Fig. 1. When ladder 20 is fully retracted, crank 60 is moved laterally to engage arm 62 between ribs 64, locking the ladder in the withdrawn position. Other locking arrangements may be used if desired.

The described device is a very effective simulation of a fire truck in action. When crank 60 is released, ladder 20 extends and figure 45 appears to climb the ladder. Similarly, when crank 60 is operated, the ladder 20 retracts and figure 45 appears to descend the ladder. The arrangement is simple to operate and substantially fool-proof, thus enhancing its value as a toy or model.

While a specific embodiment of the invention has been shown and described in detail to illustrate the application of the principles thereof, it will be understood that the invention may be

otherwise embodied without departing from such principles.

What is claimed is:

1. An extension ladder arrangement comprising, in combination, a first ladder section swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; a cable arrangement interconnecting said slide carriage, and said first and second ladder sections; means operable to raise the ladder; and means connected to said slide carriage and operable to draw the same inwardly; said cable arrangement being operative, upon operation of the ladder raising means, to draw said slide carriage and second section outwardly and said slide carriage, in moving inwardly, operating said cable arrangement to draw said second section in and to lower said ladder.

2. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; means operable to raise the ladder; a crank on said support; a cable connecting said crank to said slide carriage to draw the latter inwardly; and mechanism operable by inward movement of said slide carriage to draw said second section inwardly and to lower the ladder; said mechanism being operative, upon raising of the ladder, to draw said slide carriage and said second section outwardly.

3. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; spring means operable to raise the ladder; a crank on said support; a cable connecting said crank to said slide carriage to draw the latter inwardly; and mechanism operable by inward movement of said slide carriage to draw said second section inwardly and to lower the ladder; said mechanism being operative, upon raising of the ladder, to draw said slide carriage and said second section outwardly.

4. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated;

a cable arrangement interconnecting said support, said slide carriage, and said first and second ladder sections; means operable to raise the ladder; and means connected to said slide carriage and operable to draw the same inwardly; said cable arrangement being operative, upon operation of the ladder raising means, to draw said slide carriage and second section outwardly and said slide carriage, in moving inwardly, operating said cable arrangement to draw said second section in and to lower said ladder.

5. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; a cable arrangement interconnecting said support, said slide carriage, and said first and second ladder sections; spring means operable to raise the ladder; and means connected to said slide carriage and operable to draw the same inwardly; said cable arrangement being operative, upon operation of the ladder raising means, to draw said slide carriage and second section outwardly and said slide carriage, in moving inwardly operating said cable arrangement to draw said second section in and to lower said ladder.

6. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; means operable to raise the ladder; a crank on said support; a first cable connecting said crank to said slide carriage to draw the latter inwardly; a second cable connected to said slide carriage and said support and passing over the outer end of said second ladder section, said second cable pulling said second section inwardly as said slide carriage is retracted; and mechanism associated with said support and said ladder sections and operable to lower the ladder as the second section is retracted and to extend said second section as the ladder is raised; said second cable extending said slide carriage as said second section is extended.

7. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; spring means on said support engaged with said first section and biasing the ladder to a raised position; a crank on said support; a first cable connecting said crank to said slide carriage to draw the latter inwardly; a second cable connected to said slide carriage and said support and passing over the outer end of said second ladder

section, said second cable pulling said second section inwardly as said slide carriage is retracted; and mechanism associated with said support and said ladder sections and operable to lower the ladder as the second section is retracted and to extend said second section as the ladder is raised; said second cable extending said slide carriage as said second section is extended.

8. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; means operable to raise the ladder; a crank on said support; a first cable connecting said crank to said slide carriage to draw the latter inwardly; a pulley on the outer end of said second section; a second cable connected to said slide carriage and said support and passing over said pulley, said second cable pulling said second section inwardly as said slide carriage is retracted and mechanism associated with said support and said ladder sections and operable to lower the ladder as the second section is retracted and to extend said second section as the ladder is raised; said second cable extending said slide carriage as said second section is extended.

9. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; a crank on said support; a first cable connecting said crank to said slide carriage to draw the latter inwardly; a second cable connected to said slide carriage and said support and passing over the outer end of said second ladder section, said second cable pulling said second section inwardly as said slide carriage is retracted; and a third cable secured to the inner end of said second section and to said support and passing over the outer end of said first section; and said third cable lowering the ladder as said second section is retracted; said third cable extending said second section as the ladder is raised, and said second cable extending said slide carriage as said second section is extended.

10. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; a crank on said support; a first cable connecting said crank to said slide carriage to draw the latter inwardly; a second cable connected to said slide carriage and said support and passing over the outer end of said second ladder section, said

second cable pulling said second section inwardly as said slide carriage is retracted; and a third cable secured to the inner end of said second section and to said support and passing over a pulley on the outer end of said first section; and said third cable lowering the ladder as said second section is retracted; said third cable extending said second section as the ladder is raised, and said second cable extending said slide carriage as said second section is extended.

11. An extension ladder arrangement comprising, in combination, a support; a first ladder section pivotally mounted on said support and swingable between a raised and a lowered position; a second ladder section telescopically related to said first section; a slide carriage telescopically related to and guided in said second section for reciprocation along the length thereof; and a figure mounted on said slide carriage for simulating movement up and down said second section as said slide carriage is reciprocated; spring means on said support engaged with said first section and biasing the ladder to a raised position; a crank on said support; a first cable connecting said crank to said slide carriage to 25

5 draw the latter inwardly; a pulley on the outer end of said second section; a second cable connected to said slide carriage and said support and passing over said pulley, said second cable pulling said second section inwardly as said slide carriage is retracted; and a third cable secured to the inner end of said second section and to said support and passing over the outer end of said first section; and said third cable lowering the ladder as said second section is retracted; said third cable extending said second section as the ladder is raised, and said second cable extending said slide carriage as said second section is extended.
